ATTORNEYS.

UNITED STATES PATENT OFFICE.

AMABLE S. TUÑEZ, OF EASTON, PENNSYLVANIA, ASSIGNOR OF ONE-FOURTH TO MORRIS LEVIN, OF PHILADELPHIA, PENNSYLVANIA; ONE-FOURTH TO HARRY GORDON, OF BEVERLY, NEW JERSEY; ONE-FOURTH TO CHARLES RISER, OF PHILADELPHIA, PENNSYLVANIA; AND ONE-FOURTH TO HIMSELF.

MEANS FOR MOUNTING WINDOWS.

Application filed May 19, 1927 Serial No. 192,503.

My invention relates to an improvement in windows and more particularly to an improved means for mounting swinging windows.

5 The object of my invention is to provide means, for the support of a window, so constructed as to enable the window to be swung into fully open position, or when desired to enable the window to be retained in a partially open position.

The device in accordance with my invention is adaptable for the support, more especially, of windows of the type adapted to be swung on a horizontal axis and it is of special advantage for the support of windows of the type adapted to be both raised and lowered in a vertical plane and to be swung on a horizontal axis.

Having indicated, in a general way, the nature and purpose of my invention, I will now proceed to a detailed description thereof with reference to the accompanying drawings illustrative of a preferred embodiment and in which:

25 Fig. 1 is a front view, partly broken away, of a window embodying my invention.

Fig. 2 is a vertical sectional view of the subject of Fig. 1 with the window sash partially open.

30 Fig. 3 is a partial cross-sectional view of the window shown in Fig. 1, showing supporting means for the window in accordance with my invention.

Figs. 4, 5 and 6 are detail views showing 35 the supporting device for the window, in accordance with my invention, the window being shown in closed, partially open and fully opened position respectively.

In the drawings *a* indicates a window sash 40 provided with a pane of glass *b*. *a'* indicates an upper sash provided with a pane of glass *b'*, but my invention will be fully described by reference hereafter to the sash *a*, or lower sash only. The sash *a* is connected on each 45 side to a stile *c*. The stiles are slidably mounted in the window frame *d*, being connected by the usual sash cords to the usual sash weights to facilitate raising and lowering of the sash which is adapted to slide with 50 the stiles.

The sash *a*, as has been indicated, is con-

nected on each side to a stile *c*, which serves to support the window, and my invention relates to the connecting means between the sash and stile. To the sash is secured a 55 U-shaped fitting *e*, which is pivotally secured, by means of a bolt or rivet *f*, to a fitting *g* secured to the stile. The fitting *g* or the stile if it be made hollow is provided with an arcuate slot *h* positioned above the bolt *f* and 60 formed about the bolt *f* as a center, through which extends a pin *i* carried by the fitting *e*.

A latching member *j* is provided with a Y-shaped aperture *k* and with a slot *l*, the ends of which are recessed. The member *j* is 65 provided with a projection or tail *m*. The member *j* is positioned within the fitting *g* opposite to the fitting *e* with the end of pin *i* extending through the Y-shaped aperture *k*. The member *j* is secured to the fitting *g* 70 by means of a stud *n*, which passes through the slot *l*. Adjacent the tail *m* is a pin *o* extending from fitting *g*.

In the lower portion of the sash there is provided a right angled hole *p* extending 75 from the under surface of the lower cross piece of the sash to the upper surface outside of the pane of glass. The end of the aperture outside of the pane of glass is adapted to be closed by means of a pivoted cover plate *q*. 80

As will now be observed, the sash *a* is pivotally connected to the stile *c*, through the medium of fittings *e* and *g* and bolt or rivet *f*, and may be swung open or closed about bolt *f* as a pivot.

85 When the sash is fully closed the member *j* will be in the position shown in Figure 4, that is, supported from the stud *n*, which is engaged in the right hand recessed end of slot *l*. If the sash be swung downwardly when it reaches a half open position, the pin *i* will engage the end of the right hand branch *k'* of the aperture *k* and further opening movement of the sash will cause the member *j* to be moved bodily and about pin *i*, so as to release 90 stud *n* from the recessed end of slot *l*. Movement of the sash to a fully opened position will result in movement of member *j* to an extent sufficient to engage stud *n* in the left hand end of slot *l* and the sash will be supported in open position through the engagement of pin *i* and pin *n* with the left hand 100

end of slot l and the end of branch k' of aperture k , respectively, as shown in Figure 6. When the sash is closed the member j is returned to the position shown in Figure 4, as is obvious.

If now it is desired to retain the sash a in a partially open position, when the sash has been opened a distance such that the pin n has been displaced from the right hand recessed end of slot l and has become engaged in the left hand recessed end of the slot, the sash is given a crossing movement, which causes the pin i to be backed out of the branch k' of aperture k , which in turn permits member j to drop by gravity about pin n as a center and enter pin i in the branch k'' of aperture k . When pin i is entered in branch k'' a slight opening movement of the sash contacts the pin with the end of the branch and the sash will be supported in a partially open position, through the engagement of pin i and pin n with the left hand end of slot l and the end of branch k'' of aperture k , respectively, as shown in Figure 5. When the sash is closed, the member j is returned to the position shown in Figure 4.

If it be desired to obtain ventilation without opening of the sash at all, such may be accomplished by partially or fully swinging the cap q away from the aperture p in the lower cross member of the sash, thus permitting the passage of air from outside of the window pane into a room.

It will be understood that my invention is applicable to windows which are supported for swinging only, as well as to windows which are both slideable and swingable, and it will further be understood that the window may be pivoted to its stile, the stile being so formed as to accommodate the latching member j with elimination of the fitting g .

Having now fully described my invention, what I claim and desire to protect by Letters Patent is:—

1. In a window, in combination, a stile provided with an arcuate slot, a sash, means affording a pivotal connection between the stile and sash, a displaceable latching member carried by the stile and a pin, carried by the sash and extending through the arcuate slot in the stile, said pin being adapted to be engaged by the latching member to retain the sash in fully opened position and said latching member being adapted to be displaced in an opening followed by a closing movement of said sash to permit said pin to be engaged by the latching member to retain the sash in a partially opened position.

2. In a window, in combination, a sash, a stile, means affording a pivotal connection between the sash and stile, a latching member provided with a Y-shaped aperture displaceably secured to the stile, a pin carried by the sash and extending through said Y-shaped aperture in the latching member, said pin be-

ing adapted on swinging of the sash on its pivot to enter one arm of said Y-shaped aperture and effect displacement of said latching member on partial opening of the said window followed by a closing movement, whereby on further opening movement of said sash said pin will enter and contact with the end of the other arm of said Y-shaped aperture whereby said latching member will retain the sash in a partially opened position.

3. In a window, in combination, a sash, a stile, means affording a pivotal connection between the sash and stile, a latching member having an arcuate slot and a Y-shaped aperture formed therein, a pin secured to said stile and extending through said arcuate slot, a pin secured to said sash and extending through said Y-shaped aperture, said last mentioned pin being adapted to enter one arm of said Y-shaped aperture and cause displacement of said latching member when the sash is given an opening and closing movement, said latching member thereby permitting said last mentioned pin to enter and contact with the end of the other arm of said Y-shaped aperture to retain the sash in a partially opened position.

4. In a window, in combination, a stile, a sash, means affording a pivotal connection between the stile and sash, a displaceable latching member carried by the stile and a pin, carried by the sash, said pin being adapted to be engaged by the latching member to retain the sash in fully opened position and said latching member being adapted to be displaced to permit said pin to be engaged by the latching member to retain the sash in a partially opened position.

5. In a window, in combination, a stile, a sash, means affording a pivotal connection between the stile and sash whereby the sash may be moved from a closed to an open position, and means permitting a movement of the sash from closed to open position and acting upon a partial opening of the sash followed by a partial closing thereof to hold the sash in an intermediate position.

6. In a window, in combination, a stile, a sash, means affording a pivotal connection between the stile and sash whereby the sash may be moved from a closed to an open position, and means permitting a movement of the sash from closed to open position and acting upon a partial opening of the sash followed by a partial closing thereof to hold the sash in an intermediate position, said means being positioned, upon movement of the sash from the intermediate position towards closed position, to permit a movement of the sash to open position.

In testimony of which invention, I have hereunto set my hand, at De Land, Florida, on this 21st day of April, 1927.

AMABLE S. TUNEZ.
